COMBINATION ROTARY BRUSH AND BRUSHING AGENT DISPENSER

William Mack, 79-11 41st Ave., Elmhurst 73, N.Y.
Filed Aug. 2, 1963, Ser. No. 299,500
13 Claims. (Cl. 15-29)

This invention relates to a power driven rotary brush in association with means for dispensing a brushing agent to the rotating brush; and more particularly concerns a rotary tooth brush including means for supplying dentifrice to the brush as the same rotates.

It has been suggested that rotary brushes such as toothbrushes or the like include self contained holders for dentifrice or other brushing agents which is to be supplied to the rotating brush. However in such devices, the holder for the brushing agent is located remotely from the brush and various tubings, ducts or passages of extended length are required to pass the contents of the holder to the brush. The capacity of such holders is quite limited and with the small diameters of the tubings, ducts or passages, clogging and incidental problems materially reduce the practicality of the devices.

Accordingly, an object of this invention is to provide a power driven brush such as a toothbrush or the like, together with a holder or container for dentifrice or other brushing agent, which is of a structure and location relative to the brush which permits the passage of brushing agent directly to the brush without intervening ducts, passages or tubings.

Another object of this invention is to provide a device of the character described, wherein the holder for the brushing agent may be of substantial capacity, yet allowing the device as a whole to be of a compact nature which lends itself to ready manipulation in use.

A further object of this invention is to provide in a device of the character described, an improved brushing agent holder having contours which augment the functional and esthetic characteristics of the device as a whole.

Yet another object of this invention is to provide an improved rotary toothbrush having an improved dentifrice holder arranged for removable association therewith; the holder being quickly and readily replaced when the contents thereof are exhausted, by a similar prefilled holder.

Still another object of this invention is to provide in a device of the character described, casing means for holding a reversible motor for rotating a brush, together with battery means for energizing the motor and reversing switch means operable by a ring shaped member on the casing means, which ring shaped member also provides means for mounting the dentifrice holder thereon and for allowing the removal of the casing cover means to allow for replacement of the battery means.

Yet a further object of this invention is to provide for use with a power driven, rotary brush, improved holder means for a brushing agent which is to be supplied to the rotary brush; such holder being of compact form yet having substantial capacity, and being of a walled construction which permits the contents thereof to be passed to an orifice located adjacent the brush upon lightly squeezing outer wall portions; together with a brush guard at the forward end of the holder which is movable in a manner to provide valved closure means for the holder orifice.

Still another object of this invention is to provide in a motor driven rotary brush having battery means for energizing the motor and improved switching means for effecting a reversal of the rotation of the brush.

Other objects of this invention will in part be obvious and in part hereinafter pointed out.

In the drawings:

FIG. 1 is a longitudinal side elevational view of a rotary brush device embodying the invention, with a portion thereof in section;

5 FIG. 2 is a transverse section taken on the line 2-2 of FIG. 1;

FIG. 3 is an exploded view showing the switching elements of the device and the actuating means therefor; and

10 FIG. 4 is an exploded view showing the combination guard and valved closure for the dispensing holder.

Referring in detail to the drawings, 10 designates a rotary toothbrush and associated dentifrice holder and dispenser, embodying the invention. The same comprises 15 essentially a toothbrush assembly 11 mounted for rotation at the forward end of a metal casing 12, together with a tubular dentifrice holder generally indicated at 13, removably mounted in relation to casing 12. Within the casing 12 is disposed reversible motor means generally indicated at 14, which is energized by a battery 15 also disposed in said casing; the motor means 14 being operatively connected to the brush assembly 11 for rotating the same in either direction.

The brush assembly 11 comprises a conical brush element 16 of the dental polishing type, having a rearwardly extending stem 17 which is connected to an elongated flexible shaft connecting member 18 of nylon or light gauge spring wire. The dentifrice holder 13 is formed of blown or cast thin walled plastic to provide a receptacle of the squeeze bottle type. Holder 13 comprises an outer wall 19 tapering toward the forward end thereof, an end wall 20 at the forward end thereof which is formed with a central opening 20A and one or more dispensing openings 21 therein, and a rearwardly disposed end wall 22 30 with an externally threaded neck portion 23 extending rearwardly thereof.

A passage tube 24 is axially disposed within holder 13 to form the inner wall thereof, said tube 24 being connected at its rear end to neck portion 23 by a bushing 25. The stem 17 and shaft connecting member 18 of the brush assembly 11 pass longitudinally through tube 24, which is formed adjacent its forward end with an annular rib 26 for supporting the rotatable stem 17.

A conical brush guard 27 of a soft plastic or rubber material is non-removably, rotatably mounted on front end wall 20 of holder 13 and held in place by the forwardly disposed portion 28 of tube 24 which projects through the central opening 20A in end wall 20 and extends through a central opening 29 in the rear wall 29A of guard 27 registering with opening 20A and terminates in an annular outwardly extending flange portion 28A which engages the inner surface of wall 29A of guard 27. Guard wall 29A is formed with a dispensing opening 30 and as guard 27 is adapted to be rotated about its axis 45 on tube portion 28, the opening 30 may be registered with one of the dispensing openings 21 in holder 13 to allow the contents C, such as dentifrice, thereof to be dispensed by way of said registering openings 21, 30.

The conical wall 31 of guard 27 extends about brush element 16 in spaced relation thereto, with its outer edge 32 located to expose the bristles of brush element 16 in a conventional manner. The dentifrice dispensed from openings 21, 30 in response to light squeezing of holder wall 19, passes outwardly along the inner surface of guard 27 to the bristles of brush element 16. Guard 27 serves to hold back the corner portions of the mouth when device 10 is in use to brush the front surfaces of the rear teeth, thus avoiding the irritating contact of the brush with the inside of the cheek. In addition, guard 27 provides valved closure means for the dispensing orifices 21

of holder 13 by suitable angular rotation thereof to displace opening 30 thereof with respect to openings 21.

The holder 13 and guard 27 provide a removable unit which allows the same after exhaustion of its contents C, whether liquid, paste or the like, to be replaced by a new prefilled unit, such contents C being sealed within holder 13, by guard 27 in its sealing position relative to holder 13.

Brush 16 is rotated through its connected flexible, self aligning member 18 which is frictionally gripped at its rear end in a spring collet 33 fixed to the forward end of motor shaft 34 on motor means 14. Motor means 14 is of the reversible D.C. type housed in a metal motor casing 35 including a cylindrical side wall 36 and a rear end wall 37 formed with a central opening 38 through which projects a contact button 39 which is in electrical contact with a conductive washer 40; an insulating washer 41 separating casing wall 37 from washer 40; and an insulating washer 42 separating contact button 39 from the motor means 14.

The forward end of casing wall 36 is externally threaded as at 43 to receive threaded wall portion 44 of the outer casing 12. The open end of motor casing 35 is closed by a combination terminal and switch contact disc 45 of dielectric laminated phenolic material and formed with a central opening 45A to pass motor shaft 34. Disc 45 has peripheral contact with an annular flange portion 46 at the forward end of casing wall 36 and is held in place by means of an annular metal shell member 47 comprising a flanged portion 48 spun over flange portion 46. Shell member 47 also includes a channeled portion 49 receiving and tightly clamping the peripheral portions of disc 45; and a cupped portion 50 for enclosing peripheral portions of movable annular switch actuating member 51.

Switch actuating member 51 is connected to a ring shaped member 52 fluted on its outer surface to allow the same to be readily grasped and rotated. Member 52 is coaxially related to collet 33 and is in substantially flush arrangement with the rear portion of holder 13 and the forward end of casing 12. Member 52 includes an annular, radially and inwardly extending web portion 53 and an axially disposed annular flange 54 forming a hub into which is press fitted an axial, tubular extension 55 of switch actuating member 51 whereby member 51 has angular movement in response to movement of ring member 52.

Tubular extension 55 is internally threaded to receive the externally threaded neck portion 23 of holder 13; thus allowing holder 13 to be screwed onto or unscrewed from extension 55, when ring member 52 is held against movement.

Motor means 14 is energized by battery 15 of the conventional dry cell type disposed in the rear portion of casing 12, the battery 15 making negative contact through the usual spring 56 making contact with the end wall 12A of casing 12. A conductive path is established through the threaded connection between casings 12 and 35 and motor means 14 is electrically connected to the casing 35 as hereinafter described.

Terminal and switching connections for motor means 14 is provided on disc 45 and comprises a pair of substantially semi-circular segmental switch contactor elements 57, 58 of spring brass which are riveted at their respective central portions to disc 45 as at 59, 60, through lugs 61, 62. A conductive strip 63 extends from contactor element 57 through an opening in disc 45 to conductive washer 40 to establish contactor element 57 as the positive connection to battery 15, while a conductive strip 64 extends from contactor element 58 through an opening in disc 45 and terminating in an offset spring portion 65 which makes resilient electrical contact with the inner surface of casing wall 36 to establish contactor element 58 as the negative connection to battery 15 by 75

way of electrically interconnected casings 12, 35 and spring 56.

The outer end portions of contactor elements 57, 58 are bent outwardly and away from the disc 45 as at 65, 65A, 66, 66A respectively and the paired adjacent end portions 65, 66; and 65A, 66A are bridged by underlying fixed contact members 67, 68 mounted on disc 45 and respectively connected to the brushes of motor means 14 by conductive strips 69, 70, respectively extending from contact members 67, 68. The inturned ends of contactor element portions 65, 66; 65A, 66A, extend toward the contact members 67, 68 in slightly spaced relation thereto.

The motor 14 is connected to battery 15 to effect rotation of brush member 16 in a desired direction by operation of switch actuating member 51 through limited angular movement of ring member 52; member 51 being provided on its inner face with four equiangularly spaced hemispherical projections 71 disposed on a circle having a radius equal to that of a circle upon which segmental contactor elements 57, 58 are located.

The projections 71 on member 51 are so located that a slight angular movement of ring member 52 in either direction will cause a camming action in respect to the contactor element portions 65, 66; 65A, 66A, to bring either paired contactor portions 65, 66A or paired contactor portions 66, 65A into engagement with bridging contact members 67, 68; thus establishing connections between the motor means 14 and battery 15 with a selected polarity to cause rotation of the motor means 14 in a corresponding direction.

The spring action of contactor element portions 65, 66; 65A, 66A, is effective to return ring member 52 to its neutral or open circuit position, through their action on the hemispherical projections 71 on switch actuating member 51, when ring member 52 is released. The annular wall 51A of member 51 is notched at diametrically opposite points as at 72 to receive therein the lugs 61, 62 which thus act as stop means for limiting the angular displacement of ring member 52, to provide for the necessary camming and switching movements described above.

When torque applied to ring member 52 exceeds that required for the switching action, then ring member 52 effects a solid coupling action with casing 35, allowing casing 12 to be unscrewed from casing 35 to permit replacement of battery 15.

A gasket 73 fixed to flange 48 and the forward end of casing wall 36 and compressed by a shouldered portion 74 of casing 12 seals the compartment holding battery 15 from the ingress of moisture thereto. As gasket 75 fixed to web 53 of ring member 52 and having a lip portion 75A bearing against the cupped portion 50 of shell member 47 provides a liquid tight seal against the ingress of moisture into the switching mechanism. A combination shaft seal member 76 and face seal 77 are supported on the spring collet 33 which is fixed to motor shaft 34. Seal 77 thus has a floating relation relative to the central sealing lip portion 51B of actuating member 51 which is formed with a central, tapered clearance opening 51C to freely pass the collet 33 and shaft 34 and thereby provides a liquid tight seal against the ingress of moisture.

It is understood that the holder 13 is formed of suitable material such as synthetic plastic including polyethylene or the like, with a wall thickness which readily responds to a squeezing action to propel the contents C of the holder toward the openings 21, 30. Holder 13 is readily unscrewed from tubular extension 55 by fixing ring shaped member 52 with one hand and rotating holder 13 in the proper direction with the other hand. Guard 27 and holder 13 are removed together as an integral unit. Brush 16 with its connecting member 18 will also come away with the disconnected holder 13, being disconnected at spring collet 33 which provides the usual frictional connection with member 18.

While the device 10 has been particularly shown and

described in the form of a toothbrush in association with a paste or liquid dentifrice holder, it is understood that with some modifications, such device may also be embodied for use for a variety of grinding, polishing, cleaning and related operations, where the device may be associated with a self-contained dispenser for abrasive, cleaning or polishing agents of a wide range of viscosities including thin liquids and heavy pastes.

Thus, the device of the instant invention is readily applicable for use as a portable manicuring brush; type cleaner, spot remover and shampooing device; jewelry cleaner and polisher; grinder; and the like.

As various changes might be made in the embodiment of the invention herein disclosed without departing from the spirit thereof, it is understood that all matter herein shown or described shall be deemed illustrative and not by way of limitation, except as set forth in the appended claims.

What is claimed is:

1. A rotary brush device comprising casing means, motor means within said casing means, a brush element disposed forwardly of one end of said casing means, an elongated element coupling said brush element and said motor means, an elongated holder for carrying a brushing agent, interengageable means on one end of said holder and said casing means for removably mounting said holder on said casing means, said holder having a dispensing opening at the other end thereof for passing brushing agent to said brush element, and said holder including passage means extending longitudinally thereof, said elongated coupling elements extending through the passage means on said holder.

2. A rotary brush device comprising casing means, a motor within said casing means, a brush element disposed forwardly of one end of said casing means, an elongated member coupling said brush element and the shaft of said motor, an elongated tubular holder for carrying a brushing agent, said holder comprising outer and inner walls and end walls connecting said inner and outer walls at the opposite ends thereof, the end wall at the forward end of said holder being formed with a dispensing opening located adjacent said brush element for passing brushing agent toward said brush element, cooperating means on the rear end wall of said holder and a forward portion of said casing means for removably mounting said holder on said casing means, said coupling member extending longitudinally through the inner tubular wall of said holder.

3. A device as in claim 2 and further including a guard member disposed adjacent said brush element, said guard member having a rear end wall rotatably mounted on the forward end wall of said holder, the rear wall of said guard member having a through opening for selective registry with or displacement from, the dispensing opening in the forward end wall of said holder in response to angular displacement of said guard member relative to said holder.

4. A device as in claim 2 wherein the outer tubular wall of said holder is of conical shape tapering toward the forward end thereof, and the rear end wall thereof includes an axially disposed threaded portion, said casing means including closure means at the forward end thereof, said closure means including axially disposed threaded means for threaded engagement with the thread portion of said holder.

5. A device as in claim 1 wherein said motor is reversible, battery means within said casing means, circuit means including reversing switch means electrically connecting said motor and battery means, a ring shaped member located between said casing means and the rear portion of said holder and arranged for limited angular movement about the axis of said motor shaft and actuating means responsive to angular movement of said ring shaped member in either direction for selectively actu-

ing said reversing switch means to rotate said motor shaft in a corresponding direction.

6. A device as in claim 5 and further including a dielectric member at the forward end of said casing means for mounting said reversing switch means, said switch means including fixed contacts and movable contacts, said actuating means including means for engaging said movable contacts to bring a selected combination of fixed and movable contacts into electrical contact upon angular movement of said ring shaped member in a selected direction.

7. For use with a rotary brush device having casing means, rotating means within said casing means, a brush element and an elongated connecting member extending from said brush element for coupling engagement with said rotating means; a holder for a brushing agent to be applied to said brush element, said holder comprising a tubular outer wall of compressible plastic material, a tubular inner wall, end walls connecting said inner and outer tubular walls at the opposite ends thereof, said connecting member passing through said inner tubular wall of the holder, a dispensing opening in one of said end walls, and means on the other end wall for removably mounting said holder on a forward portion of said casing means.

8. For use with a rotary toothbrush having casing means, rotating means within said casing means, a brush element and an elongated connecting member for coupling said brush element to said rotating means; a holder for brushing agent to be applied to said brush element, said holder comprising an elongated walled member including a pair of concentric tubular portions interconnected at their opposite ends to form an elongated annular chamber for holding brushing agent, one end of said holder being formed with a dispensing opening, the outer tubular portion of said holder being compressible to urge brushing agent towards and through said dispensing opening, and means on the other end of said holder for removably mounting said holder on a forward portion of said casing means with the elongated connecting member extending through the inner tubular portion of said holder.

9. A rotary toothbrush comprising casing means closed at one end and open at the other end, motor means within said casing means and having a forwardly projecting motor shaft extending through the open end of said casing means, means for closing the forward open end of said casing with a central opening therein for passing said motor shaft, a brush element longitudinally spaced from the open end of said casing means and having a stem portion coaxially related to said motor shaft, elongated coupling means for connecting said motor shaft and the stem of said brush element, an elongated tubular holder for carrying dentifrice, said holder including a compressible outer wall, cooperating axially disposed means on a rear portion of said holder and said casing closing means for removably mounting said holder on said casing means, said holder including a tubular inner wall for passing said elongated coupling means therethrough, the forward end of said holder being located adjacent said brush element and being formed with a dispensing opening whereby compression of the outer wall of said container will cause dentifrice from said container to pass outwardly through said dispensing opening to said brush element.

10. A rotary toothbrush comprising a first casing having a cylindrical side wall and closed at one end thereof and open at the other end thereof, reversible motor means within said casing, a second casing for enclosing said motor means, said first casing being removably mounted relative to said second casing, a dielectric contact and terminal member at one end of said second casing, battery means within said first casing and arranged to make electrical contact with the motor within said second casing, terminal and switching contacts on said dielectric member, circuit means connecting said motor and battery to said contacts, movable switching means

for changing the circuit means connections to reverse said motor, a ring shaped member for actuating said switching means, said ring shaped member being coaxially related to the shaft of said motor and located immediately forward of the open end of said first casing, said ring shaped member being angularly displaceable, contacts on said dielectric member providing stop means engageable with cooperating portions of said ring shaped member for limiting the angular movement of said ring shaped member, a tubular dentifrice holder having means at one end thereof for removably mounting said holder on an axially disposed portion of said ring shaped member, a brush element at the forward end of said container, axially disposed, longitudinally extending means coupling said brush element with said motor shaft, a dispensing opening in the forward end of said holder for passing dentifrice from said container to said brush element, said ring shaped member being coupled to said second casing whereby upon applying a given torque to said ring shaped member in excess of that required to actuate said switching means, said first casing may be detached from said second casing.

11. A rotary toothbrush comprising a tubular first casing open at one end, a tubular second casing within said first casing open at one end and coaxially related to said first casing, the open ends of said casings being adjacent each other, cooperating means detachably connecting said casings, a reversible motor within said second casing, battery means within said first casing, circuit means connecting said motor and said battery, dielectric closure means at the open end of said second casing, switching means on said closure means including fixed and movable contacts, switch actuating means rotatably mounted on said second casing, means for rotating said switch actuating means comprising a ring shaped member coaxially related to said casings and located adjacent the open end of said first casing, circuit means connecting the contacts of said switch means with said motor and battery, a tubular dentifrice holder coaxially related to and located forwardly of said ring shaped member, cooperating means on said holder and said switch actuating means for removably mounting said holder on said switch actuating means, said holder including a tubular inner wall and a tubular outer wall, end walls connecting the tubular inner and outer walls at the opposite ends thereof, a rotatable brush element disposed forwardly of the forward end of said holder, coupling means extending through said inner tubular wall connecting said brush element and the shaft of said motor, the forward end wall of said holder having a dispensing opening for passing dentifrice from said holder to said brush element, said

switch contacts being selectively interconnected to provide for reversal of said motor in response to limited angular movement of said ring shaped member.

12. A rotary toothbrush comprising an outer casing open at one end thereof for holding battery means, an inner casing open at one end thereof removably mounted within said outer casing, reversible motor means within said inner casing, the open ends of said casings being adjacent each other and cooperating means on the open end portions of said casings for detachably interconnecting said casings, a dielectric contact mounting member at the open end of said inner casing, switching means including switching and terminal contacts on said contact mounting member, means for actuating said switching means including a rotatable switch actuating member, means for mounting said rotatable actuating member on said dielectric member, and manually operable rotatable means operatively connected to said rotatable switch actuating member for imparting angular movement to said switch actuating member, circuit means for connecting said motor means and battery means with said switching and terminal contacts on said dielectric member, a brush element, elongated means for coupling said brush element with said motor means, dentifrice holder means extending along said coupling means and including a compressible wall and a dispensing opening adjacent said brush element, and coating means on said holder and said rotatable switch actuating member for removably mounting said holder on said rotatable switching actuating member.

13. A device as in claim 12 and including gasket sealing means between the adjacent open end portions of said casings, and gasket sealing means between said manually operable rotatable means and said switching means.
